(57) **CLAIM**

We claim the ornamental design for a speaker, as shown and described.

DESCRIPTION

FIG. 1 is a front, right perspective view of the speaker;
FIG. 2 is a front, elevation view thereof;
FIG. 3 is a right side, elevation view thereof, the left side, elevation view being a mirror image thereof;
FIG. 4 is a back, elevation view thereof;
FIG. 5 is a top, elevation view thereof;
FIG. 6 is a bottom, elevation view thereof; and,
FIG. 7 is a sectional view thereof taken along line 7—7 of FIG. 2.

The broken lines showing an exemplar speaker case, stand, feet, portions of a grille, control openings, controls, and a vent are for illustrative purpose only and form no part of the claimed design.
